UNITED STATES PATENT OFFICE.

ROBERT H. KEATON, OF SAN FRANCISCO, CALIFORNIA.

DESIGN FOR AN AUTOMOBILE TIRE.

Application filed November 24, 1920. Serial No. 426,298. Term of patent 3½ years.

To all whom it may concern:

Be it known that I, ROBERT H. KEATON, a citizen of the United States, residing in city and county of San Francisco and State of California, have invented a new, original, and ornamental Design for Automobile Tire, of which the following is a specification, reference being had to the accompanying drawing, forming part thereof.

Figure 1 shows a perspective view of a portion of a tire showing my design. Fig-

ure 2 shows a plan view of the same. Figure 3 shows a sectional view taken on the line $x-x$ of Fig. 2.

I claim:

The ornamental design for an automobile tire, as shown.

ROBERT H. KEATON.
